DESIGN FOR A KNIFE RACK

Albert E. Rosenberg, New York, N. Y.

Application August 11, 1942, Serial No. 107,878

Term of patent 14 years

To all whom it may concern:

Be it known that I, Albert E. Rosenberg, a citizen of the United States of America and a resident of the county of Queens, city and State of New York, have invented a new, original, and ornamental Design for a Knife Rack, of which the following is a specification, reference being had to the accompanying drawing, forming a part thereof.

In the drawing:

Figure 1 is a front perspective view of a knife rack, showing my new design.

Figure 2 is a side view in elevation of the knife rack, the side not shown being similar to the side shown.

Figure 3 is a top plan view of Figure 1.

I claim:

The ornamental design for a knife rack, as shown and described.

ALBERT E. ROSENBERG.
